FIRE EXTINGUISHING APPARATUS

Henry E. Braloff, Rockville Centre, N. Y.

Application May 2, 1942, Serial No. 441,423

2 Claims. (Cl. 169—35)

This invention relates generally to fire extinguishing apparatus and is more particularly directed to a device for extinguishing incendiary bombs and blazing fragments thereof, by the use of sand or a similar granular or pulverized material.

While my invention is primarily directed to the provision of a device for discharging sand or the like for extinguishing fire, as the description proceeds it will become manifest that it is susceptible of numerous other applications in dispensing granular or pulverized material, for various purposes, all of which, I would have it understood, are deemed to come within the scope of my invention, as defined by the appended claims.

It is recognized that sand or a similar granular or pulverized material is the most efficient agent for extinguishing incendiary bombs of the magnesium and other types, commonly used in warfare, as currently practiced, the usual method that is followed in combatting the bomb being to throw the sand upon the blazing bomb or bomb fragments by means of a shovel, spade or other suitable implement. For this purpose, the civilian defense authorities recommend that pails of sand and the necessary shovel or the like, be kept available for immediate use by the civil population, to combat the potential fire hazard that is presented by the incendiary bombs and their fragmentation. However, because of the unsightliness of the sand pails and shovels, it is found that they are usually relegated to some out-of-way place for storage, as in the basement or cellar of a building, so that considerable delay may ensue in getting them to the point where they are to be employed in extinguishing a fire bomb. Further, the bulkiness and weight of the sand-laden pail, combined with that of the essential shovel or spade, in many instances, may also contribute to delay in combatting a blazing bomb, by retarding the progress of the person carrying them to the location of the bomb.

Therefore, it is the primary object of this invention to provide a simple and economical container for a supply of sand or similar material, which may be readily maintained at or carried to the point where it is to be used and the sand or other granular fire-extinguishing agent discharged or emptied therefrom upon the blazing bomb or bomb fragment in a concentrated stream.

A further important object of my invention is to provide a fire-extinguishing device, as aforesaid, which will not only conserve the use of the

extinguishing agent, but permit of the attainment of greater efficiency in smothering a blazing or smoldering incendiary bomb, my device making it possible to direct a concentrated stream of the granular material upon the blaze with expedition and in a manner to cut off the blaze-sustaining supply of oxygen and quickly render the bomb harmless.

Another object of this invention is to provide a fire-extinguishing device having the foregoing characteristics and advantages, which may be readily handled and requires a minimum of space for storage, so that it may be kept at hand for immediate use, as in upright position in a convenient closet, or, if desired, by hanging it on a wall or the like by means of a bracket attached to the main body portion thereof. This makes it possible to distribute a number of extinguishers about the premises, instead of having the fire-extinguishing agent concentrated in one place, in one or more pails, as is customary, because of the bulk and unsightliness of the pails.

It is also an object of my invention to provide a method of producing a container of fibrous material from which sand or similar granular material may be dispensed, whereby the possibility of the packing of the material within the container with a resulting interruption of the flow therefrom will be entirely eliminated, so that the material will issue from the container in a constant concentrated stream until the supply is exhausted.

My invention also contemplates a container which may be variously produced and employed in dispensing granular or pulverized material other than sand, where a steady and concentrated discharge of the material may be requisite or desirable.

Other objects and advantages flowing from the practicing of my invention will become manifest as the description proceeds and I would have it understood that I reserve unto myself all rights to the full range of equivalents, both in structure and avenues of use, to which I may be entitled under this disclosure.

In the accompanying drawing, I have illustrated a preferred embodiment of my invention, as it may be utilized as a portable fire-extinguisher sand gun which my device may be termed, since it permits of accurately directing the fire-extinguishing agent upon the blazing objective. Obviously, my invention may take other forms and be applied to other purposes, as hereinbefore pointed out.

In the drawing:

Figure 1 is a longitudinal section of a fire-extinguisher conforming to my invention, and

Figure 2 is a view in elevation of the device shown in the preceding figure, partly broken away to disclose the manner in which an interrupted discharge of the granular material is insured.

Referring now to the drawing in detail, in which like characters of reference are employed to designate similar parts in the several views, 1 indicates the tubular body-portion or main cylinder of the sand gun and 8 the outlet-forming cylinder or nozzle of the gun, the diameter of which is less than that of the main cylinder. The nozzle-forming cylinder or tube is concentrically mounted in the main cylinder or body-portion by means of the telescoping sleeves 9 and 10, the sleeve 9, as will be noted, preferably terminating in registration with the end 7a of said body-portion, as at 9a, while the sleeve 10, telescoped into the sleeve 9, projects beyond the end of said main cylinder in engagement with the periphery of the outlet-forming cylinder 8 entered therein, as indicated at 10a, for the reason which will become apparent.

The diameter of each of the sleeves 9 and 10 and of the nozzle-forming cylinder 8 provides for their telescopic assembly with the body-portion or main cylinder 1, as described, the tolerance between the opposed surfaces thereof insuring a tight fit that prevents their dislocation under load, so that the assembly possesses all of the attributes of a unitary structure.

In the assembly of the sleeves 9 and 10 and the nozzle-forming cylinder 8 within the body-portion 1, the inner ends of the sleeves and the nozzle 8 are relatively spaced, so as to reduce the diameter of the passage from the body-portion to the nozzle cylinder in graduated steps, the ends of said sleeves and of said nozzle-forming cylinder forming ledges or shoulder 9b, 10b and 8b, respectively. These shoulders or ledges serve to create a turbulence as the sand impinges thereupon in its tortuous mass movement in conforming contact with the defining walls of the passage, to produce the effect of a spillway in diverting the sand into the section of the passage of next smaller diameter and prevent packing of the mass and interruption of its movement through the device to the discharge end of the nozzle cylinder 8, as would result in a gun in which the reduction of the diameter of the outlet were obtained by an elongated tapering of conical wall formation. Manifestly, this turbulence results in a speeding up of the rate of movement within the mass in its central zone or core, as the thickness of the moving column of granular material is progressively diminished, to enter the nozzle-forming cylinder and issue therefrom in a steady stream, as the device is held in inverted position at the appropriate angle to direct the granular material upon the blazing objective, as shown in Figure 2 of the drawing.

By extending the sleeve 10 beyond the contiguous end of the body-portion 1, in surrounding engagement with the outlet-forming cylinder 8, the latter is reinforced in that area thereof which, otherwise, might be susceptible to bending or distortion under load, as the column of sand traverses the portion of the elongated nozzle-cylinder which protrudes beyond the end of the body-portion of the device.

The restricted discharge or outlet end of the nozzle cylinder 8 is sealed by a plug 11, while the

enlarged loading end of the main cylinder 1 is sealed by plug 12. The respective plugs 11 and 12 here shown as separable from the gun may be connected thereto by a chain or other displaceable means (not shown) to prevent their loss when removed from sealing position.

The gun is preferably loaded at its enlarged main cylinder end and when so loaded and sealed is adapted to be maintained in storage position by resting vertically upright on plug 12 as a base, although the gun may, if desired, be supported in any angular position as, for example, at the angle shown in Figure 2 of the drawing, by providing a bracket assembly on the periphery of the main cylinder (not shown) for separable connection with a wall support.

The gun may be made of any suitable material, as metal, plastic, fibre-board or the like and the internal shoulder or ledges may be formed by telescoping tubes, as herein described, or otherwise, as in a roll winding casting or spinning operation. However, in order to provide an economical device and permit of rapid production and the extensive distribution that is essential, especially under wartime conditions, I prefer to fabricate my gun of a readily obtainable spiral wound fibrous material comprising sheet paper known to the trade as chip board.

In practicing the method which I utilize for the purpose, the chip board is preferably spirally wound upon suitable mandrels to produce lengths of laminated tubing of the required diameters, the tubing of the appropriate diameters being then cut in the lengths necessary for forming the main and outlet cylinders and the two sleeves, after which the sleeves and outlet-forming cylinder are assembled within one end of the main cylinder 1, as heretofore described, under pressure applied longitudinally thereof, the outer circumference of each of the entered sections being approximately the same as the inner circumference of the section into which it is telescoped, so as to provide for the frictional engagement of the opposed surfaces in a degree which will render them inseparable without encompassing their destruction. Of course, if desired, an adhesive may be applied to the opposed surfaces but the inherent resiliency of the laminated material which renders it possible to force-fit one tube within another, makes it unnecessary.

As will be evident, a cardboard gun, produced according to my method, is light in weight, possesses the required strength and may be refilled time and again, if required. Since chip board is an inflammable material, it is desirable to protect the nozzle-forming cylinder 8 against possible ignition by accidental contact with the flames emanating from a bomb or the like, or by the heat generated thereby, and to this end it may be treated with a fireproofing material, or the nozzle may be provided with a protective sleeve or collar of asbestos or other fire-resistant composition, as indicated at 15 in Figure 2 of the drawing, the collar, preferably, embodying a flange which will overlie and cover the end of the cylinder wall, as at 15a.

From the foregoing, it will be manifest that I have provided a simple and efficient container for dispensing granular material, together with a method of producing the same, which makes it possible to provide a fire extinguisher which is especially responsive to the demand for a medium for combatting incendiary bombs, that may be effectively handled by those unskilled in fire-fighting and may be economically produced so as

to insure the wide distribution that is essential under wartime conditions.

I claim:

1. A device for dispensing granular material comprising a main cylinder, an outlet-forming cylinder of lesser diameter and a plurality of sleeves telescoped into one end of said main cylinder, one of said sleeves projecting outwardly of said main cylinder, said outlet-forming cylinder being telescopically entered in said latter sleeve, the inner ends of said sleeves and said outlet-forming cylinder providing a series of shoulders within said main cylinder, adjacent the outlet end thereof, relatively spaced to define a passage between said main cylinder and said outlet-forming cylinder having sections of different diameters, the diameters progressively decreasing toward the outlet-forming cylinder.

2. A device for dispensing granular material comprising a cylindrical body-portion, a concentric extension at one end of said body-portion of lesser diameter forming a nozzle for said device and means for progressively decreasing the diameter of the passage from said body-portion to said extension in a series of relatively spaced bore-conforming surfaces, each interposing an impediment to the movement of the granular material in massed conformation with the preceding bore-conforming surface of larger diameter to generate a movement within the mass and overcome the inertia forces of the compacted material to obtain an interrupted columnar discharge of the material from said nozzle.

HENRY E. BRALOFF.
